(57) **CLAIM**

The ornamental design for a signage assembly, as shown and described.

DESCRIPTION

FIG. 1 is a side perspective view of a signage assembly showing our new design;

FIG. 2 is a side view thereof;

FIG. 3 another side view thereof;

FIG. 4 is a front view thereof;

FIG. 5 is a rear view thereof;

FIG. 6 is a plan view thereof;

FIG. 7 is a bottom view thereof; and,

FIG. 8 is an enlarged detailed view of encircled area 8 in FIG. 1.

The broken lines in the figures show portions of the signage assembly which form no part of the claimed design.

The dashed lines in FIGS. 1 and 8 illustrate the border of enlarged detailed views and form no part of the claimed design.
